UNITED STATES PATENT OFFICE.

STANLEY D. ROBINSON, OF HAMILTON, ONTARIO, CANADA.

DESIGN FOR A HEATING-ELEMENT SECTION FOR ELECTRICAL GRATES AND THE LIKE.

59,685.

Specification for Design.

Patented Nov. 15, 1921.

Application filed June 27, 1921. Serial No. 480,940. Term of patent 3½ years.

To all whom it may concern:

Be it known that I, STANLEY D. ROBINSON, a subject of the King of Great Britain, residing in Hamilton, in the county of Wentworth and Province of Ontario, Canada, have invented a new, original, and ornamental Design for Heating-Element Sections for Electrical Grates and the like, of which the following is a specification, reference being had to the accompanying drawing, forming part thereof.

The figure is a face view of a heating element section for electrical grates and the like showing my new design.

I claim:

The ornamental design for a heating element section for electrical grates and the like, as shown.

STANLEY D. ROBINSON.
